GRINDING WHEEL DRESSER

Ferdinand J. Henkel, Royal Oak, Mich., assignor
to Lamina Dies and Tools, Inc., Berkley, Mich.,
a corporation of Michigan

Application December 29, 1945, Serial No. 637,847

9 Claims. (Cl. 125—11)

1

This invention relates to grinding machines, and in particular to wheel dressing devices for such machines.

One object is to provide a simple yet accurate grinding wheel dresser wherein the dressing tool may be instantly attached or removed merely by placing it on a swinging rest carrying a template.

Another object is to provide a grinding wheel dresser wherein the dressing tool is carried in a holder which rests upon a base plate and in contact with a template as it is pushed manually across the face of the grinding wheel.

Another object is to provide a grinding wheel dresser as set forth in the preceding objects wherein the rest is moved toward and away from the grinding wheel by a micrometer screw mechanism.

Another object is to provide a grinding wheel dresser as set forth in the preceding objects wherein the holder carrying the dressing tool is held in position against the rest and likewise against the template by a combination of gravity and manual force, the absence of other mechanism in the grinding wheel area enabling the rest and template to be kept scrupulously clean and to be free from the errors otherwise arising in mechanism exposed to the grit thrown off by the grinding wheel being trued.

Another object is to provide a grinding wheel dresser as set forth in the preceding objects wherein the rest swings about a pivot shaft located above the dressing area so that grit thrown off by the grinding wheel will never reach the bearings of the pivot shaft and hence the latter will retain its accuracy of adjustment without the wear otherwise occurring in such devices.

Another object is to provide a grinding machine dresser as set forth in the preceding objects wherein a modified form of the invention provides a rest which is inclined to the horizontal in the dressing position of the device.

Other objects and advantages will become apparent during the course of the following description of the accompanying drawings wherein:

Figure 1 is a top plan view of a grinding wheel dresser according to a preferred embodiment of the invention;

Figure 2 is a side elevation, partly in section, of the grinding wheel dresser shown in Figure 1;

Figure 3 is an end elevation of the micrometer hand wheel and adjacent mechanism in the upper left-hand corner of Figure 1;

Figure 4 is a vertical section taken along the broken line 4—4 in Figure 1;

2

Figure 5 is a vertical cross-section taken along the line 5—5 in Figure 2;

Figure 6 is a horizontal section, partly in top plan view, taken approximately along the line 6—6 in Figure 2;

Figure 7 is a fragmentary vertical section of the dressing tool block and swinging base plate taken along the line 7—7 in Figure 2; and

Figure 8 is a side elevation similar to Figure 10.2 but showing a modification thereof employing an inclined base plate.

Referring to the drawings in detail, Figures 1 and 2 show a preferred embodiment of the grinding wheel dresser of this invention, generally designated 10, as applied to a conventional grinding machine, generally designated 11 and having the usual grinding head 12 with a forwardly projecting bearing bracket 13 containing the usual bore 14 rotatably supporting a shaft 15. The shaft 15 is provided with a flange 16 having a surface 17 serving as an abutment for a grinding wheel 18 mounted upon the reduced diameter portion 19 of the shaft 15 and held in position by a washer 20 retained by a nut 21 threaded upon a further reduced diameter portion 22 which carries a thread corresponding to that of the nut 21. The grinding wheel 18 is provided with the usual peripheral surface 23 which is to be trued or dressed by the grinding wheel dresser 10 of the present invention.

The grinding head 12 is provided with a plurality of threaded holes 24 (Figure 1) adapted to receive bolts 25 passing through bores 26 in the base portion 27 of a bracket 28 (Figure 4) and having a machined rear surface 29 engaging the similarly machined abutment surface 30 of the grinding head 12 (Figure 1). The base portion 27 of the bracket 28 is approximately annular in shape and is provided with a central aperture 31 for the passage of the bearing bracket 13. A part 32 (Figure 4) of the base portion 27 is cut away in the direction of a chord of the base portion 27 and terminates in a tangentially disposed arm 33 extending outwardly from the base portion 27.

The arm 33 of the bracket 28 is provided with elongated angled guide surfaces 34 (Figures 4 and 5) engaging similarly angled surfaces 35 of retaining plates 36 of a dove-tailed slide, generally designated 37. The dove-tailed slide 37 further includes a carriage-like plate 38 having threaded holes 39 therein adapted to receive bolts 40 passing through holes 41 in the retaining plates 36, thereby causing the elements 36, 38 and 40 to travel to and fro relatively to the arm 33 along

the angled guide surfaces 34 thereof. The bolts 40 also serve to provide an adjustment and take-up for wear in the dove-tailed slide 37 and to maintain the latter in a high precision operating condition.

The slide 37 is moved to and fro along the arm 33 by means of a nut 42 (Figure 6) movable to and fro in an elongated recess 43 in the arm 33 along a screw shaft 44 threaded through the threaded bore 45 of the nut 42. The latter is approximately T-shaped (Figure 6) and is provided with a shank 46 secured as at 47 in a transverse hole 48 in the plate 38.

The screw shaft 44 is provided with a flanged portion 49 (Figure 6) located in a recess 50 connected to the recess 43 by an enlarged bore 51 so as to permit free rotation thereof. The recess 43 at its opposite end terminates in a cavity 52 adjacent the free end of the screw shaft 44.

Beyond the flanged portion 49, the screw shaft 44 is provided with a reduced diameter portion 53 passing through a corresponding bore 54 in a circular head 55 bolted as at 56 (Figure 3) to the end 57 of the arm 33. The head 55 is provided with a cylindrical boss 58 (Figure 6) which is encircled by the rim 59 of a hand wheel 60 keyed as at 61 to the outer end of the reduced diameter portion 53 of the screw shaft 44. A button 62 additionally serves to retain the hand wheel 60 upon the end of the screw shaft 44 and secured thereto by the screw 63 threaded into the hole 64. The hand wheel flange 65 is provided with an eccentric threaded hole 66 into which is threaded the end of a knob or handle 67 for rotating the hand wheel 60. The rim 59 is provided with graduations 68 of any suitable dimension, such as in thousandths of an inch. These graduations 68 cooperate with a zero pointer 69 to indicate the travel of the slide 37 and accordingly the feed imparted thereto. The screw shaft 44 is provided with anti-friction thrust bearing assemblies 70 and 71 (Figure 6) on opposite sides of the head 55 and surrounding the reduced diameter portion 53 of the screw shaft 44.

Secured by the bolts 72 passing through holes 73 in the plate 38, is a tubular hanger 74 having threaded holes 75 therein (Figure 6) for receiving the ends of the bolts 72. The hanger 74 is provided with a bore 76 (Figure 2) having annular bearing recesses 77 and 78 at its opposite ends for receiving anti-friction bearing assemblies 79 and 80 respectively. The outer race of the bearing assembly 80 is held in position by a cylindrical cap 81 bolted as at 82 to the hanger 74.

The inner races of the bearing assemblies 79 and 80 are mounted at the opposite ends of the reduced diameter portion 83 of a pivot shaft 84, the lower end of which is threaded as at 85 to receive a retaining nut 86. The upper end of the shaft 84 is enlarged as at 87 to receive a bore 88 in the hub 89 of a swinging arm 90, the shaft 84 being enlarged as at 91 to engage a countersink 92 (Figure 2) in the hub 89. The hanger 74 and shaft 84 are inclined upwardly relatively to the slide 37.

The arm 90 is provided with a plate-like depending portion 93 of roughly triangular shape having a transverse bore 94 (Figures 6 and 7) in which is secured a stop screw 95 having a head 96 engaging the adjacent surface 97 of the slide 37. By this means, the arm 90 is accurately located in a vertical position relatively to the slide 37. Secured to the bottom edge 98 of the depend-

ing portion 93 of the arm 90 is a plate-like tool rest 99, the connection being made by bolts 100 passing through holes 101 therein into the threaded holes 102 formed in the edge 98.

The upper surface 103 of the rest 99 is accurately machined to flatness and carries a template bar 104 secured thereto as by the bolts 105 threaded into the holes 106 therein. The template bar 104 has secured to a vertical edge thereof a template 107 having an accurate contact surface 108 engaged by the correspondingly accurate front surface 109 of a contact strip 110 secured to the dressing tool holder 111 in the form of a block (Figure 1). The dressing tool holder 111 has an accurately machined bottom surface 112 adapted to rest upon and slide along the upper surface 103 of the rest 99. The contact surface 108 of the template 107 may be straight or curved or otherwise configured, depending upon the configuration of the grinding wheel 18, a straight template being shown merely for purposes of illustration.

The tool holder 111 in its front face 113 is provided with a socket 114 in which is mounted the shank 115 (Figure 1) of a diamond dressing tool 116 having a diamond or other extremely hard cutting element 117 mounted in the forward end thereof. The diamond tool 116 is held in position by the set screw 118 threaded into the transverse hole 119 (Figure 1). The parts are so arranged and dimensioned that the diamond 117 is positioned in alignment with and approximately at the end of a horizontal diameter of the grinding wheel 18.

The modification shown in Figure 8 is similar to the preferred form of the invention shown in Figures 1 to 7 inclusive, except that the bracket 28 is mounted on the grinding head 12 in an inclined direction such that the rest surface 103 of the rest 99 is inclined to the vertical, thereby causing the tool holder 111 to be similarly inclined, and the diamond 117 to be aligned with an inclined diameter of the grinding wheel 18. By this construction the tool holder 111 is urged downwardly by gravity against the template 107.

In either form of the invention, when the wheel dresser is not in use and the grinding machine 11 is being used, the tool holder 111 is removed from the rest 99 and stored in a safe location. The arm 90 is then swung upwardly around its pivot shaft 84 until it is out of the way, as shown by the chain lines in Figure 8. In the form of the invention shown in Figures 1 to 7 inclusive, the arm 90 will occupy a similar location relatively to the carriage 38 and arm 33, but more nearly horizontal in its position.

In the operation of either form of the invention, when it is desired to dress or true the peripheral surface 23 of the grinding wheel 18, the arm 90 is swung from its raised to its lowered position, as determined by the engagement of the head 96 of the stop screw 95 against the surface 97 of the dove-tailed slide 37. The dressing tool holder 111 is then placed upon the upper surface 103 of the rest 99, which has previously been carefully wiped off, and pushed forward until its contact strip 109 engages the template 107 at a location to one side of the grinding wheel 18. The hand wheel 60 is then turned to move the slide 37 the necessary amount to bring the diamond 117 into close proximity to the grinding wheel surface 23 for a suitable depth of cut. The grinding wheel 18 is then rotated and the tool holder 111 moved along the template 107 while 75 being held firmly in the operator's hand, there-

by taking a cut across the peripheral surface 23 of the grinding wheel 18. The hand wheel 60 is then moved a prescribed amount according to the graduations 68 with reference to the zero pointer 69 to move the slide 37 to take the second cut across the periphery 23 of the grinding wheel 18. This procedure is repeated until the periphery 23 is suitably trued.

While I have shown and described my invention in detail, it is to be understood that the same is to be limited only by the appended claims, for many changes may be made without departing from the spirit and scope of my invention.

What I claim is:

1. A wheel dresser for grinding machines comprising a support attachable to the grinding machine, a rest connected to said support and extending adjacent said wheel, a template mounted on said rest, a wheel dressing tool holder slidably supported on said rest in engagement with said template, and a wheel dressing tool mounted on said tool holder, said rest being positionable in an inclined arrangement relatively to said wheel, and said tool holder being urged by gravity down said inclined rest into engagement with said template.

2. A wheel dresser for grinding machines comprising a support attachable to the grinding machine, a slide reciprocable on said support, means for precisely moving said slide toward and away from said wheel, a rest movably mounted on said slide and extensible into a position adjacent said wheel, a template mounted on said rest, a wheel dressing tool holder slidably supported on said rest in engagement with said template, and a wheel dressing tool mounted on said tool holder.

3. A wheel dresser for grinding machines comprising a support attachable to the grinding machine, a slide reciprocable on said support, means for precisely moving said slide toward and away from said wheel, a rest pivotally mounted on said slide and extensible into a position adjacent said wheel, a template mounted on said rest, a wheel dressing tool holder slidably supported on said rest in engagement with said template, and a wheel dressing tool mounted on said tool holder.

4. A wheel dresser for grinding machines comprising a support attachable to the grinding machine, a slide reciprocable on said support, means for precisely moving said slide toward and away from said wheel, a pivot mounting arranged on said slide, a rest connected to said pivot mounting and swingable therearound into and out of proximity to said wheel, a template mounted on said rest, a wheel dressing tool holder slidably supported on said rest in engagement with said template, and a wheel dressing tool mounted on said tool holder.

5. A wheel dresser for grinding machines comprising a support attachable to the grinding machine, a slide reciprocable on said support, means for precisely moving said slide toward and away from said wheel, a pivot mounting arranged on said slide, a rest connected to said pivot mounting and swingable therearound into and out of proximity to said wheel, a template mounted on said rest, a wheel dressing tool holder slidably supported on said rest in engagement with said template, and a wheel dressing tool mounted on said tool holder, said pivot mounting having its pivot axis inclined upwardly relatively to said wheel.

6. A wheel dresser for grinding machines com-

prising a support attachable to the grinding machine, a slide reciprocable on said support, means for precisely moving said slide toward and away from said wheel, a pivot mounting arranged on said slide, a rest connected to said pivot mounting and swingable therearound into and out of proximity to said wheel, a template mounted on said rest, a wheel dressing tool holder slidably supported on said rest in engagement with said template, and a wheel dressing tool mounted on said tool holder, said pivot mounting having its pivot axis inclined upwardly relatively to said wheel and said rest depending therefrom toward said wheel.

15 7. A wheel dresser for grinding machines comprising a support attachable to the grinding machine, a slide reciprocable on said support, means for precisely moving said slide toward and away from said wheel, a pivot mounting arranged on said slide, a rest connected to said pivot mounting and swingable therearound into and out of proximity to said wheel, a template mounted on said rest, a wheel dressing tool holder slidably supported on said rest in engagement with said template, and a wheel dressing tool mounted on said tool holder, said pivot mounting having its pivot axis inclined upwardly relatively to said wheel and said rest depending therefrom toward said wheel, said rest and said tool holder having 20 relatively flat contacting portions arranged for slidable engagement therebetween.

8. A wheel dresser for grinding machines comprising a support attachable to the grinding machine, a slide reciprocable on said support, means for precisely moving said slide toward and away from said wheel, a pivot bearing mounted on said slide, a pivot shaft mounted in said bearing, an arm connected to and depending from said shaft, a rest extending transversely from said arm into 35 proximity to said wheel and having a relatively flat upper surface portion thereon, a template mounted on said rest, a wheel dressing tool holder having a bottom surface slidably engageable with said upper surface portion and with said template, and a wheel dressing tool mounted on said tool holder.

9. A wheel dresser for grinding machines comprising a support attachable to the grinding machine, a slide reciprocable on said support, means for precisely moving said slide toward and away from said wheel, a pivot bearing mounted on said slide, a pivot shaft mounted in said bearing, an arm connected to and depending from said shaft, a rest extending transversely from said arm into 50 proximity to said wheel and having a relatively flat upper surface portion thereon, a template mounted on said rest, a wheel dressing tool holder having a bottom surface slidably engageable with said upper surface portion and with said template, and a wheel dressing tool mounted on said tool holder, said pivot shaft having its axis inclined upwardly relatively to said slide.

FERDINAND J. HENKEL.
